[57] CLAIM

The ornamental design for a ball striker or the like,
substantially as shown and described.

DESCRIPTION

FIG. 1 is a perspective view of my new ball striker or
the like showing the front and left side views;

FIG. 2 is a top plan view thereof;

FIG. 3 is a right side elevational view thereof;

FIG. 4 is a rear elevational view thereof;

FIG. 5 is a bottom plan view thereof; and

FIG. 6 is a front view of a modified embodiment of my
invention.

FIG. 1

FIG. 3

FIG. 4

FIG. 2

FIG. 5

FIG. 6
